4 Claims. (Cl. 315—3.5)

The invention relates to a device having a travelling wave tube, in which the electron beam reciprocates with a helical delay line which at its ends is coupled to the input and output conductor respectively which are connected together by a cylindrical wave guide which closely encloses the tube wall. The invention further relates to a travelling wave tube destined for such a device.

In the devices of the above type already used, the problem presents itself that in the space between the helical delay line and the cylindrical wave guide which encloses the tube wall, parasitic modes of oscillation may occur. These may give rise to the generation of undesired oscillations. It is already known to provide in this space damping material through a part of the length of the delay line in form of dissipating material which is provided on a cylinder around the tube wall or as a thin metal or carbon layer on the inside or outside of the insulating tube wall.

It is also known to provide for this purpose dissipating material on a dielectric cylinder which is located between the tube wall and the delay line and which encloses the latter substantially throughout the whole of its length. The drawback of the known means to avoid undesired oscillations and feedback coupling between output and input wave guide is that in particular at the higher frequencies the oscillations are prevented in a limited frequency range only which decreases the usability of the plant.

The object of the invention is to provide a construction which has advantages with respect to the known constructions and which is composed in a simple manner.

According to the invention, in a device of the type described above, a disc-shaped conductor is passed through the wall of the tube between the ends of the helical delay line, which conductor on the outside joins the wall of the cylindrical wave guide which connects the input and output wave guide and in which this disc-shaped conductor is connected to a conductive tube which encloses the helical delay line with its insulating supporting rods closely and which tubular conductor extends over half to three fourths of the length of the delay line.

With the construction according to the invention, the feedback path between output and input wave guides is restricted by the tube which encloses the helical conductor and as a result of its smaller diameter, the cut-off frequency hereof is considerably higher than that of the cylindrical wave guide which encloses the wall of the tube. As a result of the high cut-off frequency it is not necessary to provide the conductive tube with damping material, since this tube will suppress parasitic modes of oscillation which may occur. Of course it is necessary that the connection of the leading-in disc to the wave guide wall provides a satisfactory high-frequency connection because otherwise feedback coupling might occur along this path.

In order that the invention may readily be carried into effect, one embodiment thereof will now be described, by

2

way of example, with reference to the accompanying drawing, the sole figure of which is a cross-section through the most important elements of part of the device according to the invention.

5 In the figure, reference numeral 1 indicates the hollow input wave guide and reference numeral 2 the hollow output wave guide of an amplifier device having a travelling wave tube 3. Input and output wave guide are connected by a circular-cylindrical wave guide 4, within which the glass wall 5 of the travelling wave tube is located at a short distance. Two metal discs 6 and 7 respectively are sealed to the wall 5 which discs form the connection with the wave guides 1 and 2 respectively. A short glass cylinder 8 is sealed to the other side of the disc 6, which cylinder comprises the parts of the electron gun not shown. The disc 7 supports, via a short glass cylinder, the collector electrode not shown. The helical delay line 9 is provided between the discs 6 and 7 by means of some transition parts, which line is supported by 10 three ceramic rods 10. A third metal disc 11 is passed through the wall in the proximity of the disc 7, which disc 11 makes contact with the transition of the wave guides 2 and 4, in which a satisfactory tight high-frequency connection is ensured. The disc 11 supports the 15 satisfactorily conductive tube 12 consisting of copper-nickel which extends through approximately two thirds of length of the delay line. The copper-nickel is not only satisfactorily conductive but also non-magnetic. With the exception of the damping material present on the helical delay line through part of its length, which material serves to avoid generating and is not shown, no damping means are present in or about the travelling wave guide. Although the disc 11 is shown at the end of the tube 12, it may be provided, without objection, in the middle of 20 the tube and may there also join the wave guide 4.

What is claimed is:

1. A travelling-wave tube arrangement comprising an envelope, a rigidly supported helical delay line within the envelope, input and output wave-guide means coupled to 40 the respective ends of the helical delay line, a first cylindrical wave-guide surrounding the envelope connecting the input and output wave-guides, a tubular conductor constituting a second cylindrical wave-guide having a higher cut-off frequency than said first cylindrical wave-guide 45 surrounding and extending about half to three-fourths of the length of the delay line, and a disc-shaped conductor between the ends of the helical delay line connecting the first and second cylindrical wave-guides for preventing feed-back coupling between the input and output wave-guides.

2. A travelling-wave tube arrangement as claimed in claim 1 in which the second cylindrical wave-guide is positioned within the envelope and is supported by the disc-shaped conductor which extends through the envelope.

3. A travelling-wave tube as claimed in claim 2 in which the helical delay line is supported by insulating support rods.

4. A travelling-wave tube as claimed in claim 2 in 60 which the second cylindrical wave-guide is a metal tube.
